APPARATUS FOR FILLING CONTAINERS WITH
CARBONATED LIQUIDRudolph H. Breeback, Baltimore, Md., assignor to Crown
Cork & Seal Company, Inc., Philadelphia, Pa., a cor-
poration of New York

Filed Feb. 20, 1963, Ser. No. 259,822

12 Claims. (Cl. 141—56)

The present invention relates to an apparatus for filling containers with a carbonated liquid and, more particularly, to an apparatus to provide a "quiet" filling of containers with carbonated liquids.

In the filling of containers with carbonated liquids, for example, beer or soft drinks, it has been the practice to first place the empty container under pressure slightly less than, the same as, or slightly more than the pressure at which the carbonated liquid is subsequently flowed into the container. This stage of the filling cycle is known in the art as "counter-pressure" stage. Once a container has been placed under counter-pressure, then the carbonated liquid is flowed into the container while the gas within the container is vented from the same to a body of gas under pressure. It has been the usual practice to vent the gas back to the reservoir of the filling machine which contains the carbonated liquid under a superposed body of gas at a predetermined pressure. In some carbonated liquid filling systems, the venting of gas from the container differs in that the gas is vented to a body of gas under pressure separate from the body of gas superposed above the liquid in the filling machine reservoir. In my prior United States Patent No. 2,953,169, there is disclosed one such system for a separate counter-pressuring and venting of the container. The system of my aforementioned patent produces a high quality product, as the product is not contaminated with shop air either in the containers or in the reservoir. Once the filling and venting stage has been completed, the container is then removed from the filling head of the filling machine and is immediately closed by applying a crown if the same is a bottle or by seaming a can end thereto if the same is a can. In some instances, it is desirable to relieve the pressure in the head space of the container prior to breaking the seal of the container with the filling head. This practice is known as "sniffing" and usually is accomplished in high pressure filling by placing the head space into open communication with atmosphere.

In recent years, the height of fill in a container being filled with a carbonated liquid has been accurately and uniformly controlled by means of a ball float adapted to close the vent passage when the liquid in the container has reached a predetermined height. The result of closing off the vent passage causes pressure to build up in the head space of the container and stop the flow of liquid into the container. When this has been accomplished, the filling valve of the filling head is then moved to positively shut off the liquid flow and gas flow passages and the container is then lowered away from sealing engagement with the filling head. Such ball floats used with filling heads for controlling the height of fill are disclosed in United States Patent No. 2,794,455 to Day and Breeback and my United States Patents No. 2,770,263 issued November 13, 1956 and No. 2,953,169 dated September 20, 1960. However, the use of the ball float as a valve to close off the lower end of the vent passage has had some difficulty especially in high speed operation of rotary filling machines as the containers are quickly lowered away from the filling head and the pressure trapped behind the ball float or that pressure in the vent line between the ball float and the filling valve, when the filling valve is moved to closed position, is discharged downwardly into the liquid just as the container breaks its seal.

2

This surge of gas into the filled container causes an agitation or disturbance of the carbonated liquid therein resulting in foaming and short-filled containers. Because short-filled containers must be rejected and the contents 5 of the same cannot be saved, the losses resulting from such short-filled containers over a period of time become quite substantial.

An important object of the present invention is the provision of a filling machine in which the filling cycle 10 for carbonated liquids is improved in that a quiet fill is obtained especially during the critical portion of the filling cycle, that is, breaking the seal of the container from the filling head.

Another object of the present invention is to provide an 15 improved filling machine for filling containers with carbonated liquids, the filling machine having an improved filling head resulting in a filling cycle which is shorter, thus, increasing output capacity of the filling system and reducing the possibility of producing foaming containers 20 or containers of short fill.

A further object of the present invention is to provide an 25 improved filling machine for filling containers with carbonated liquid, the filling machine having means thereon for reducing the pressure in the vent passages prior to the container being broken away from the filling head.

A still further object and advantage of the present invention is to provide an improved filling head having a 30 valve arrangement thereon which results in easier removal of the filled container from sealing engagement with the head.

These and other objects and advantages of the invention will appear more fully in the following specification, claims and accompanying drawings in which:

FIGURE 1 is a front elevational view of a filling head 35 of the present invention with parts being shown in section and in broken lines for the purpose of clarity and with the lower portion of the filling head being omitted;

FIGURE 2 is a sectional view of the lower portion of 40 the filling head of FIGURE 1, the view showing a container supported on a container-supporting platform and in sealing engagement with the filling head;

FIGURE 3 is a vertical sectional view of the filling head, partly in elevation and taken substantially on the 45 line 3—3 of FIGURE 1, the view additionally illustrating the filling head attached to a portion of a filling machine shown in phantom lines;

FIGURE 4 is an elevational view similar to FIGURE 1 of the filling head of the present invention but showing 50 the movement of the filling valve element and its operating arms through the various stages of the filling cycle;

FIGURE 5 is a rear elevational view of the disc valve 55 element of the filling head of the present invention;

FIGURE 6 is a sectional view taken on the line 6—6 of FIGURE 5;

FIGURE 7 is a front elevational view of the seat face 60 of the body member of the filling head;

FIGURE 8 is a sectional view taken on the line 8—8 of FIGURE 7 and exposing the gas packages for venting 65 gas from the container;

FIGURE 9 is a fragmentary sectional view taken on the line 9—9 of FIGURE 7 and illustrating the liquid passage from the seat face of and through the body member of the filling head, this passage being connected 70 to the reservoir of the filling machine.

Referring now to the drawings wherein like character and reference numerals represent like or similar parts, and, more particularly, to FIGURES 1, 2 and 3, the filling head of the present invention is generally designated at 10 and includes a body member 12 having a downwardly extending nozzle portion 14 and a disc-type valve 16 cooperating with the body element and movable

to various positions during the filling cycle of a container. In more detail, the filling head 10 is secured to the peripheral flange 18 of a reservoir carrying superstructure 20 of a rotary filling machine (not shown). The superstructure 20 carries a reservoir 26 for carbonated liquid L and a superposed body of gas G under pressure. The gas G is usually carbon dioxide. The rotary filling machine may be of the type disclosed in my aforementioned United States Patent No. 2,953,169, and it will be understood that a plurality of such filling heads 10 are carried about the periphery of the flange 18. Usually, there are 60 to 72 of such filling heads. A container supporting platform 22 is positioned immediately beneath and in alignment with each filling head 10, the platform being vertically reciprocable in a rotary filling table 24. The container supporting platforms 22 are moved upwardly and downwardly in any suitable manner such as by air pressure cylinders on the platform or by cams in the path of rotation of the filling table 24, the motion of the platforms being in timed sequence with infeed conveyors, movement of the filling valve in the filling head and take-off conveyors.

In brief, infeed conveyors feed containers C successively to the container supporting platforms 22 as they pass an infeed station and the platforms immediately elevate the container vertically until the lip of the container is in sealing engagement with the lower end of the downwardly extending nozzle portion 14 of filling head 10. The filling valve element 16 is then rotated to a position where the container is placed under counter-pressure. In this position, the liquid passages through the filling head are closed to flow of liquid but gas under pressure, either from the superposed body of gas G of reservoir 26 or from a separate body of gas under pressure is flowed through a gas passage in the filling head into the container. The gas passage through the filling head may be the same gas passage used for subsequently venting gas from the container or it may be a separate gas passage. After the pressure of the gas in the container has built up to a desired pressure, the filling valve element 16 is then moved to a filling and vent position wherein the liquid passage through the filling head is opened to flow and the gas passage for venting the gas from the container is opened to flow. Carbonated liquid from reservoir 26 is flowed into the container C, and as the level of liquid in the container C rises, the gas within the container C is vented through the gas passage of the filling head to a body of gas under pressure, for example, the superposed body of gas G above the liquid in the reservoir 26 or to a separate body of gas under pressure as disclosed in my aforementioned United States Patent No. 2,953,169. Once the container C has been filled to a desired level, the level being controlled by the rise of liquid in the container to a point where the venting of gas therefrom is stopped, the filling valve element 16 is moved to the shut-off stage where the liquid passage and gas passages are positively closed to flow at points spaced from the container C. The container supporting platform 22 is then lowered to break the seal of the container C with the filling head, and the filled container is transferred from the platform onto the take-off conveyor where it is suitably closed.

The present invention in its broadest sense involves the reducing of the pressure in the gas vent passage after the filling valve 16 has been moved to the shut-off stage. A certain amount of gas pressure is usually trapped in the vent passage and in the present invention, such vent passage below the point where the filling valve closes the same, is vented to atmosphere so that when the seal of the container with the filling head 10 is broken, there will be no sudden surge or spurt of gas downwardly onto the surface of the liquid. This completely eliminates foaming of the container due to agitation of the carbonated liquid.

Sniffing of the container head space to atmosphere may

be necessary in such filling machine installations which utilize a high-pressure filling system. In installations where the liquid in the reservoir of the filling machine is under a pressure of the superposed body of gas in the excess of, for example, thirty pounds per square inch, the industry considers the machine to be a high-pressure system. Usually in such systems it is also necessary to directly sniff the head space of the container to atmosphere to reduce the pressure therein. On the other hand, where the system is a low-pressure system, for example, a system where the pressure on the liquid in the reservoir is less than thirty pounds per square inch but higher than atmospheric pressure, it has been generally found unnecessary to sniff the head space of the container prior to breaking the seal of the container with the filling head.

The embodiment of the invention which will be described hereinafter in detail is intended for use in filling flat-top containers such as cans with carbonated liquids such as soft drinks or beer. However, the specific structure of the filling head disclosed herein may be modified for filling containers other than cans, and it will also be appreciated by those skilled in the art that the particular filling valve described in connection with the filling head can be other than that which is known as a "disc-type" valve.

In more detail, the body member 12 of filling head 10 is provided with a rear substantially planar face 28 which is bolted to the outer planar face 30 of the flange or mounting plate 18. A gasket 32 is interposed between the faces 28 and 30. The outer surface of the body member 12 is circularly recessed as indicated at 34 and a gasket 36 is positioned in recess so that the outer surface of the gasket forms a seat face 38. A stud 40 projecting centrally from the seat face 38 of the valve body 12 is adapted to rotatably receive the disc valve 16. Spring means 42 in the nut 44 retain the disc valve 16 on the stud 40 with the proper amount of pressure being exerted by the face 36 of the valve against the seat face 38 of the body member.

Referring now specifically to FIGURES 2 and 3, it will be noted that the downwardly extending nozzle portion 14 of the body member 12 is detachably secured to the body member by a ring nut 46. The lower face of the nozzle portion 14 is substantially horizontal and is provided with a compressible sealing ring or gasket 48 which is adapted to be engaged by the head of the top of the container C.

Referring now to FIGURES 7, 8 and 9, it will be noted that the body member 12 is provided with a first liquid passage 50 which opens on the seat face at 52. The other end of passage 50 is provided with an enlarged recess 54 having a ball 56 therein to serve as a check valve in case a container leaks or does not seat properly against the sealing ring 48, the ball closing the liquid passage from the reservoir in a known manner. The recess 54 receives one end of a conduit 58 which connects the liquid passage 50 in the body member 12 to the lower portion of liquid of the reservoir 26 as indicated at 60 in FIGURE 3.

Body member 12 also includes a gas passage 62 extending from the seat face at 64 to the rear planar face 28. The gas passage 62 communicates with a passage 65 (FIGURE 3) in the mounting plate or ring 18, the passage 65 in turn communicating with a body of gas under pressure such as the superposed body of gas G above the liquid L in reservoir 26. While the present embodiment of filling head is shown with only one gas passage therethrough, it being understood that said gas passage can be used to supply gas under pressure to the container during the counter-pressure stage and to vent gas from the container during the filling stage, it also being within the scope of the present invention to use separate passages through the body member, one being for gas during the counter-pressure stage and the other being for the venting of gas during the filling stage as is known in the art.

The downwardly depending nozzle portion 14 of the body member 12 is provided with a liquid passage 66 (FIGURE 2) opening at the seat face as indicated at 68 (FIGURES 1, 4 and 7). The liquid passage 66 may extend into a plurality of branches 70 each having a nozzle tip 72 for flowing liquid into the containers and down the side walls of the same. A pair of branch gas passages 74 and 76 extending from the seat face at 78 and 80 respectively connect with a gas passage 82 which extends downwardly through the nozzle portion 14 to an enlarged chamber or recess 84. A tubular fitting 86 is carried in the enlarged recess 84 and is provided with an annular seat 88 for a ball float 90. The ball float 90 is supported within a cage member 92 detachably supported by the nozzle portion 14 in the recess 84.

Referring now to FIGURES 5 and 6 of the drawings, it will be noted that the valve member 16 is provided with the usual operating arms 94 and 96 for engaging suitable cams positioned in their path of movement with the rotary superstructure, the cams rotating the valve member 16 on the stud 40. FIGURE 5, which is a rear elevational view of the disc valve element 16 discloses the face 36 of the same which cooperates with the seat face 38 of the body member 12. It will be noted the valve member 16 is provided with a liquid passage 98 opening to the face 36 at the openings 100 and at 102. The passage 98 is made by milling out a portion of the seat face 36 as shown in FIGURE 6 and rounding the corners as indicated at 104 and 106. The milled out portion for the passage 98 is provided with a shoulder as indicated at 108, and a plate 110 having apertures therein which define the openings 100 and 102 respectively is then brazed or soldered into position. By forming the liquid passage 98 in this manner, such liquid passage may be made entirely smooth with suitable curves in the same at the points where it changes direction, thereby providing for the smooth flow of carbonated liquid therethrough. By eliminating burrs and sharp changes of direction in the liquid passage in the valve member 16, turbulence in the carbonated liquid is reduced, thereby increasing the overall effectiveness of the filling head for a quiet fill.

Valve member 16 is also provided with a gas passage 112 therethrough which has openings to the seat face 36 at three places as indicated at 114, 116 and 118. The purpose of providing the three openings or ports 114, 116 and 118 will be more fully explained later in the specification.

The valve member 16 is also provided with a passage 120 opening to the valve face 36 at 122 and to atmosphere through a tubular fitting 124 as indicated at 126. The passage 120 is adapted to have its opening or port 122 on the seat 36 aligned with the opening or port 78 in the body member 12 when the valve 16 is in the shut-off position or stage so that the gas passage 82 between the seat face 38 and the ball float 90 is vented to atmosphere. A more detailed discussion of this feature of the present invention will appear later in the specification.

Body member 12 is provided with a fitting 128 which has a lug 130 thereon. The lug 130 provides a stop to prevent overtravel of the valve element at the limits of rotation of the same. In more detail, when the valve member 16 is rotated to the shut-off position as shown in FIGURE 1, a radially extending lug 132 on the valve member 16 engages the lug 130 to prevent overtravel. When a cam strikes the lower operating arm 96, it will move the valve member 16 clockwise as viewed in FIGURE 4 to the counter-pressure stage and then a second cam striking the arm 96 will move the valve member 16 further clockwise to the filling and venting stage. In the filling and venting stage, as shown in broken lines in FIGURE 4, the tubular fitting 124 which provides the outlet 126 to atmosphere for the passage 120, extends above the periphery of the valve member and acts as a stop to prevent overtravel of the valve member 16.

machine of the present invention may be described as follows:

5 An empty container C is moved onto the filling platform 22 of the rotary filling table 24 from an infeed conveyor at a suitable infeed station. The platform 22 with the empty container C thereon is then moved vertically as the table 24 rotates until the upper lip or edge of the container engages the resilient ring or gasket 48 of the filling head 10 immediately thereabove and makes a seal therewith.

10 While this is occurring, the filling valve 16 of filling head 10 is in the shut-off position identified on FIGURE 4 by a letter A. It will be noted that the openings or ports 100 and 102 of liquid passage 98 in filling valve 16 are not in alignment with the openings or ports 52 and 68

15 for the liquid passages 50 and 66 respectively of the body member 12. Likewise, the gas passage 112 in the filling valve member 16 has its openings or ports 114, 116 and 118 out of alignment with the openings or ports 78 and 80 for gas passages 62 and 65. However, the passage 120

20 has its opening or port 122 in open communication with the opening or port 78 on the seat face 38 of body member 12 and thus places the gas passage 82 from the ball float 90 to the seat face in open communication with atmosphere.

25 When the filling valve member 16 is moved to the position indicated by the letter B shown in FIGURE 4, the liquid passage 98 is moved clockwise about the axis of stud 40 but still has its openings or ports 100 and 102 on the face 36 out of alignment with the openings or ports

30 52 and 68 respectively on the face 38 of body member 12. The gas passage 112 in the filling valve member 16 will have moved to a position wherein the opening or port 118 is out of alignment with any of the gas passage openings or ports on the seat face 38, but the opening or

35 port 116 will have been placed into alignment with the opening or port 80 on the seat face 38 whereas the opening or port 114 is placed in alignment with the opening or port 64 on the seat face 38. When the valve member 16 is in this position, gas under pressure may flow through

40 the passage 65 (FIGURE 3) to the passage 62 through the passage 112 in the valve member 16 and then into the branch 76 to the passage 82 so as to discharge gas out of the tubular insert 86 into the container. This causes the container to be placed under counter-pressure so that the carbonated liquid can be flowed into the container without foaming.

45

50 After the pressure in the container has reached the predetermined value, the filling valve 16 is moved from the counter-pressure stage indicated by the letter B to the filling and vent stage indicated by the letter D. When in this position, the openings 100 and 102 of the liquid passage 98 in the valve member 16 are aligned respectively with the openings 52 and 68 in the seat face of the body member 12. Liquid then flows through the tubing 58 and liquid passage 50 into the passage 98 in the valve element 16 and from there through the liquid passage 66 and branches 70 and is discharged through the nozzles 72 down the side walls of the container.

At the time the valve member 16 is moved to the filling and venting stage D, it will be noted that the gas passage 112 in the valve has moved to a position where its openings 118 and 116 are aligned respectively with the openings 64 and 78 in the face of body member 12. The counter-pressure gas within the container can now be vented through the tubular fitting 86 and gas passage 82 through the branch 74 where it flows through the passage 112 in the filling valve member 16 and from there back to the body of gas under pressure above the carbonated liquid in the reservoir 26 by means of the passages 62 and 65.

As the liquid rises in the container C, it will eventually reach a height where the ball float 90 will be moved vertically upwardly within its cage 92 to a point where its upper portion engages the annular seat 88 on fitting 86. This will cut off the flow of vent gas through the

passages described above and the pressure then built up in the head space of the container C will increase to a point where it stops the flow of liquid into the container through the liquid passages. When this condition occurs, the filling valve member 16 is moved in a counter-clockwise direction, as viewed in FIGURE 4, from the position D to the position A which is the shut-off stage. This movement of the valve 16 will move the gas passage 112 and liquid passage 98 out of alignment with the respective gas and liquid passages in the body member 12. However, as explained above, the passage 120 in the valve member 16 will move to a point where its opening 122 is in alignment with the opening 78 in the seat face 38 of body member 12. Then gas under pressure, trapped between the ball float 99 and the seat face 38 of the body member 12 in the gas passage 82, will be relieved to atmosphere causing the ball float to drop off its seat.

The filled container C can now be lowered away from its seal with the sealing ring or gasket 43. Since the gas passages 82 have been relieved of any gas under pressure, there is no sudden surge of gas downwardly past the ball float 99 into the container to cause agitation or disturbance of the carbonated liquid. It may be desirable to snift the head space of the container just prior to breaking the seal simultaneously with or after the pressure of gas in the gas passage 82 has been reduced to atmospheric pressure. If it is desirable to snift the head space of the container, the filling head can be provided with the usual snift valve which opens the container head space directly to atmosphere so that excess pressure in the head space can be bled therefrom.

While the objects and advantages of the present invention have been fully and effectively accomplished by the methods and apparatus described, it will be understood that the methods and apparatus might be modified slightly without departing from the scope of the present invention.

Therefore, the terminology used in this specification is for the purpose of description and not limitation, the scope of the invention being defined in the claims.

What is claimed is:

1. In a filling head for filling containers with a carbonated liquid: a body member provided with a portion adapted for sealing engagement with a container, said body member including a liquid passage extending therethrough and adapted to connect a liquid reservoir under pressure with a container, said body element further including a gas passage extending therethrough and adapted to connect a body of gas under pressure with the container, a first valve means carried by said body element and operable upon rise of the level of liquid in the container to a predetermined level to close said gas passage adjacent its opening into the container before the container is removed from the filling head, and a second valve means carried by said body member and cooperating with said liquid and gas passages and operable to open said passages to establish liquid flow to the container and vent flow of gas to the body of gas, said second valve means being operable to close said liquid and gas passages after the container is filled and after said first valve means is closed at points spaced from the container, said second valve means including means to reduce pressure of gas in the portion of the gas passage between said first valve means and the point in the gas passage where said second valve means closes the same.

2. A filling head as claimed in claim 1 in which said first valve means includes a ball float carried by said body member, said ball float cooperating with said gas passage to close the same when liquid reaches a predetermined height in the container.

3. A filling head as claimed in claim 1 in which said means to reduce pressure of gas in the portion of the gas passage between said first valve means and the point

in the gas passage where said second valve means closes the same is a passage open to atmosphere and carried by said second valve means, said passage being placed in communication with the portion of the gas passage between said first valve means and the point in the gas passage where said second valve means closes the same when said second valve means is operable to close said liquid and gas passages.

4. In a filling head for filling containers with a carbonated liquid, a body member provided with a valve seat and a downwardly extending portion having a substantially horizontal face which is adapted for sealing engagement with a container, said body element including at least a first gas passage opening to said valve seat and adapted to communicate with a body of gas under pressure, said body member further including at least a first liquid passage opening to said valve seat and adapted to communicate with a liquid reservoir under pressure, said downwardly extending portion of said body member

20 including a second liquid passage opening to said valve seat and to said horizontal face and a second gas passage opening to said valve seat and to the horizontal face, a valve member cooperating with said valve seat and including at least one gas passage and at least one liquid

25 passage therein, said valve member being operable to align its gas passage with the first and second gas passages of said body element and to align its liquid passage with the first and second liquid passages of said body element to establish venting of gas from the container and liquid

30 flow to the container respectively and then operable to move its gas and liquid passages out of alignment with said gas and liquid passages respectively in said body member, a ball float valve carried by a downwardly extending portion of said body member, said ball float valve

35 cooperating with the gas passage in the downwardly extending portion of said body member to close the same and stop venting of gas from the container when liquid has reached a predetermined level in the same, and means

40 carried by said valve member and operable to reduce pressure in the gas passage in the downwardly extending portion of said body member when said valve member is moved to a position where the gas and liquid passages of the same are out of alignment respectively with the gas and liquid passages of said body member.

45 5. A filling head as claimed in claim 4 in which said last-mentioned means includes a passage in said valve member open at one end to atmosphere and having the other end thereof adapted to be aligned with the gas passage in the downwardly extending portion of said body member when said gas and liquid passages of said valve member are out of alignment with the gas and liquid

50 passages in said body member respectively.

6. A filling head as claimed in claim 5 in which said passage in said valve member open to atmosphere is placed

55 in communication with the gas passage in the downwardly extending portion of said body member after said ball float closes the gas passage and prior to removal of the container from sealing engagement with the horizontal face thereof.

60 7. A filling head as claimed in claim 4 in which said valve seat on said body member is planar and in which said valve member is a disc valve element, rotatable on said seat, and in which said pressure reducing means includes a passage in said disc valve element open at one

65 end to atmosphere and having its other end adapted to be aligned with the gas passage in the downwardly extending portion of said body member when said gas and liquid passages of said disc valve element are out of alignment with the gas and liquid passages in said body respectively.

70 8. A filling head as claimed in claim 7 including a lug carried by said body member and a pair of lugs extending radially outwardly of said disc valve element, one of said pair of lugs engaging said first-mentioned lug when said disc valve element is in a position where the gas and

liquid passages of the same are out of alignment with the gas and liquid passages in said body member, and the other of said pair of lugs engaging said first-mentioned lug when said disc valve element is in a position where the gas and liquid passages of the same are in alignment with the gas and liquid passages of said body member whereby rotation of said disc valve element between a fully open and fully closed position is limited.

9. A filling head as claimed in claim 7 in which said liquid passage in said valve member includes a groove having rounded ends in said disc valve element and a plate covering said groove and having apertures therein at the extremities thereof, said plate being flush with the surface of said disc valve element.

10. In a container filling machine for filling containers with a carbonated liquid: a filling head, a container supporting element arranged to move a container into and out of sealing engagement with the filling head, said filling head including a body member having a downwardly extending portion with a substantially horizontally extending face adapted for sealing engagement with the container, said body member having a liquid passage therethrough extending from a liquid reservoir under pressure to the horizontal face and a gas passage therethrough extending from a body of gas under pressure to the horizontal face, valve means carried by said body member and operable by a rise of liquid in the container being filled to close said gas passage and stop venting of gas from the container to the body of gas, and a second valve means operable to first open said liquid and gas passages to the respective flow of liquid into a container and gas from the container to the body of gas, said last-mentioned valve means then being operable after flow

of liquid has been stopped by said first valve means to close said gas and liquid passages at points spaced from the container, said second valve means also including means to place said gas passage between said first valve means and the point where said second valve means closes the same into open communication with the atmosphere after said second valve means has been operated to closed position and prior to said container supporting platform lowering the container from sealing engagement with said filling head.

10 11. A container filling machine as claimed in claim 10 in which said first valve means includes a ball float carried by said body member and a valve seat adjacent the lower end of said gas passage, said ball float being adapted

15 to seat against said valve seat and close said gas passage.

12. A container filling machine as claimed in claim 10 in which the means of said second valve means for placing the gas passage in open communication with atmosphere includes a passageway carried in said valve means 20 having one end continuously open to atmosphere and the other end adapted to be brought into communication with the gas passage after said first valve means has closed said gas passage.
